UNITED STATES PATENT OFFICE

129,699

DESIGN FOR A GLOBE FOR LIGHTING FIXTURES

John Cidissen, New York, N. Y.

Application June 19, 1941, Serial No. 101,573

Term of patent 14 years

To all whom it may concern:

Be it known that I, John Cidissen, a citizen of the United States of America, residing at New York city, State of New York, have invented a new, original, and ornamental Design for a Globe for Lighting Fixtures, of which the following is a specification, reference being had to the accompanying drawing, forming a part thereof, wherein:

Figure 1 is a front elevational view of a globe for lighting fixtures, showing my new design.

Figure 2 is a top plan view thereof.

I claim:

The ornamental design for a globe for lighting fixtures, as shown.

JOHN CIDISSEN.
